UNITED STATES PATENT OFFICE.

JOHN EVANS, OF SALT LAKE CITY, UTAH.

PIN.

Application filed May 9, 1922. Serial No. 559,638.

To all whom it may concern:

Be it known that I, JOHN EVANS, a citizen of the United States, and resident of Salt Lake City, in the county of Salt Lake 5 and State of Utah, have invented a new and Improved Pin, of which the following is a full, clear, and exact description.

My invention relates to a sorting pin, and aims to provide a device of this nature which 10 may be utilized to advantage in numerous applications, but which is primarily intended to be used in connection with a sorting machine of the nature illustrated in my previous application Serial #440095 15 filed January 26, 1921.

It has been found in connection with identifying pins employed in conjunction with a sorting machine of the type illustrated that a relatively great amount of 20 time was lost incident to effecting a detachment of the sorted materials from the pins with which they were associated, and in certain instances where an operator had not 25 completely opened the pin parts, a pull upon the material was liable to result in the same being torn.

Thus it is an object of the present invention to provide a sorting device or pin for materials which may be utilized to advantage in connection with a sorting machine of the type indicated, and by means 30 of which an attachment and detachment of articles from these pins may be effected in an extremely simple manner.

A further object of the present invention resides in the provision of a pin, the parts 35 of which are normally locked, so that any material associated with these parts will not be accidentally detached from the same.

A still further object of this invention is that of providing a pin, the parts of which are normally locked as aforesaid, but in 40 which these parts will be unlocked in a semi-automatic manner upon the pin reaching its final position.

With these and further objects in mind 45 my present invention aims to provide a pin comprising a plurality of parts movable with respect to each other, and a piercing element forming the pin proper, which is adapted to extend through the material to be retained, together with means whereby the pin will be caused to normally remain in a position at which it will retain said material, said pin further comprising a

structure which will permit of a movement of said pin to a releasing position.

Reference is had to the attached sheet of drawings as illustrating one practical embodiment of my invention, and it will be 60 seen in these drawings that;

Figure 1 is a side elevation of a part of a sorting machine of the nature specified, and showing a pin of my improved construction in association therewith. 65

Figure 2 is an enlarged sectional view taken along the line 2-2 and in the direction of the arrows indicated in Figure 1 showing the pin parts in locked position.

Figure 3 is a view similar to Figure 2 70 but showing the pin parts in unlocked position, and further indicating in dotted lines the position which the parts assume during the detachment of the material from the pin, and

Figure 4 is a view of a slightly modified portion of the sorting machine shown in Figures 1, 2 and 3.

In the embodiment illustrated I have shown a pin in association with a sorting 80 machine of the type indicated in my previous application, and thus in the present case the reference numeral 5 indicates a rod, which corresponds to the rod 22 of the sorting machine aforementioned, the reference numeral 6 indicating the base member or ring of the machine, corresponding to the member 12 of the previous application. However it will be noted that contrary to the construction previously indicated 85 a key is associated with the rod 5, and adjacent the lower end of the same, this key being in the nature of a sleeve 7 presenting a downwardly extending flange and a base 9, which latter co-operates with the member 6 and serves to retain the sleeve 90 in proper position.

Now with respect to the pin illustrated in detail in Figures 2 and 3 it will be noted that the same preferably includes a housing 10 providing a cutout portion 11, this housing slidably carrying a U shaped member 12, the base of which extends beyond the body of the housing and is adapted to encircle the rod 5, and when adjacent the 105 lower end of the same, the sleeve aforescribed.

The housing 10 may also carry a tab 13 presenting an identifying mark 14 where- 110 by the articles associated with the pin may

be properly sorted. The U shaped member 12 also has the end of one of its arms bent inwardly as at 15, and incident to the provision of a stop pin 16 associated with the housing a movement of the U shaped member beyond a predetermined point with respect to the housing is prevented due to the fact that the inwardly turned end 15 will engage the stop pin 16. The second 10 arm of the U shaped member 12 terminates in a point 17 which normally bridges the cutout portion 11, and it will be obvious that upon an article such as a cloth 18 having part of its body introduced into the 15 cutout portion subsequent to which the U shaped member 12 is projected to the position shown in Figure 2, that the cloth will be firmly secured to the pin.

Now with a view of providing means serving to normally retain the parts in this position it will be noted that a dog 19 is pivotally carried as at 20 by the housing 10, and this dog has one of its ends extending into a cutout portion 21 forming a part of the 25 housing 12 its opposite end being capable of being swung into the path of travel of the bent end 15 of the U shaped member 12. The dog 19 is normally retained in this position by means of a suitable type of spring 22 which presses against the rear face of the 30 last mentioned end of the dog 19 to produce this result, and to lock the member 12 normally against movement with respect to the housing when the former is projected within 35 the latter.

Thus assuming that the parts are in such a position that the bent end 15 of the member 12 lies adjacent to the stop pin 16 it will be understood that the cloth 18 may be extended into the cutout portion 11 of the housing 10, subsequent to which a movement of the member 12 inwardly with respect to the housing 10 will cause the point 17 to 40 pierce the cloth 18, and will also cause the dog 19 to move to the position shown in Fig. 2 in which a retraction of the member 12 will be prevented thus closing the pin. It is to be understood that the foregoing operation of the parts occurs when the pin is used 45 in conjunction with a sorting machine of the type specified while the pin is at the upper end of the rod. Upon this pin now being released and incident to the action of gravity, the same will slide downwardly along the rod 5, and due to the fact that the flange 8 of the sleeve 7 also extends downwardly it will be obvious that this portion will ride 50 into the cut-out part 21 of the housing 10 upon the latter reaching a position adjacent 55 the lower end of the rod.

Now upon an operator desiring to effect a detachment of the cloth 18, he can do so upon merely grasping the cloth and pulling the same sidewise, as has been shown in Figure 3. Upon this occurring the outer end 60

of the dog i. e. that part of the same which extends into the cutout portion 21, will be brought into engagement with the flange 8 of the key, and the dog will consequently be swung to the position shown in Figure 3. 70 Upon a pull upon the cloth being continued it will be obvious that incident to the engagement of this material with the edge of the cutout portion 11 of the housing 10 that the latter will be pulled downwardly to the position shown in dotted lines in Figure 3, thus in other words, retracting the point 17 and permitting the cloth to be pulled free of the point. This latter operation of course is not resorted to until the key has either been 75 completely filled or all of the clothes belonging to one batch have been placed upon the same and it will be obvious that it will not be necessary for an operator to effect a release of each cloth separately, but he will be 80 enabled to grasp all of the materials so as to effect a simultaneous retraction of all of the pin parts. Further it will be subsequently found that all of the pins are now open or in other words ready for a second sorting operation, and that also all of these pins are 85 now upon the key. This latter member may thus be detached from the rod 5 and applied to a pin rack (not shown) where the 90 pins will be available for association with materials as the same are received, the key being subsequently capable of re-association 95 with the rod.

Thus all of the objects of this invention have been accomplished, and it will be appreciated that numerous modifications might be resorted to such as for instance a rod, in lieu of employing an extraneous sleeve might comprise a body 23 as in Figure 4 formed with an integral flange 24 serving the same 100 purpose as the flange 8 shown in Figures 1, 2 and 3.

I claim:

1. A sorting pin including a housing, a member movable with respect to said housing, a point forming a part of said member, and movable with respect to said housing, said housing guarding said point, and a movable dog carried by said housing and normally engaging said member to retain 110 the same in this position.

2. A sorting pin including a housing a member movable with respect to said housing, a point forming a part of said member, and movable with respect to said housing, 115 said housing guarding said point, and a pivoted dog carried by said housing and normally engaging said member to retain the same in this position.

3. A sorting pin including a housing, a 125 member movably carried by said housing, a point forming a part of said member, said housing normally acting as a guard for said point, a bent portion forming a part of said member, a dog movable with respect to said 130

housing and having a portion of its body lying in the path of travel of said bent portion whereby to retain the parts of the pin normally in position.

5 4. A sorting pin including a housing, a U-shaped member movably carried by said housing, a point forming a part of said member said housing normally acting as a guard for said point, a bent portion forming a part of said member, a dog movable with respect to said housing and having a portion of its body lying in the path of travel of said bent portion whereby to retain the parts of the pin normally in position.

10 5. A sorting pin including a housing, a member movably carried by said housing, a point forming a part of said member said housing normally acting as a guard for said point, a bent portion forming a part of said member and adjacent the end of the same, a dog movable with respect to said housing and having a portion of its body lying in the path of travel of said bent portion whereby to retain the parts of the pin normally in position.

15 6. A sorting pin including a housing, a member movably carried by said housing, a point forming a part of said member, said housing normally acting as a guard for said point, a bent portion forming a part of said member, a dog movable with respect to said housing and having a portion of its body lying in the path of travel of said bent portion whereby to retain the parts of the pin normally in position, and means for normally forcing said dog to its normal position.

20 7. A sorting pin including a housing, a member movably carried by said housing, a point forming a part of said member, said housing normally acting as a guard for said point, a bent portion forming a part of said member, a dog movable with respect to said housing and having a portion of its body lying in the path of travel of said bent portion whereby to retain the parts of the pin normally in position, and a spring positioned within said housing and engaging said dog to retain the same in its normal position.

25 8. A sorting pin including a housing formed with a cutout portion, means providing a point for retaining an article applied to said housing, a dog carried by said housing and normally retaining said last named means in projected position, one of the ends of said dog extending into the cutout portion of the housing, and means adapted to be projected into said cutout portion to move said dog to effect a release of said means.

30 9. A sorting pin including in combination a housing formed with a cutout portion, means providing a point for retaining an article applied to said housing, a dog carried by said housing and normally retain-

ing said last named means in projected position one of the ends of said dog extending into the cutout portion of the housing, and means providing a flange adapted to extend into said cutout portion whereby upon said housing being swung, said flange will engage said dog whereby said point may be retracted.

35 10. A device of the kind described having a structure defining a non-circular opening shaped to permit the device to be slipped along a supporting rod or the like having other than a circular cross section, whereby the device is suspended from and in effect feathered on said rod, said device including, in combination, pinning means comprising a pen-point and a keeper relatively movable, means for releasably normally holding the last two parts against relative movement when the pin is in the keeper and the device is suspended to a position determined solely by gravity, and means engageable by a part of said rod thereby to release said releasable means and cause relative movement between the pen-point and its keeper to separate the two, upon imparting a swinging movement to the device about its point of suspension on said rod.

40 11. A sorting device of the kind described having a structure defining a non-circular opening shaped to permit the device to be slipped along a supporting rod or the like having other than a circular cross section, whereby the device is suspended from and in effect feathered on said rod, said device including, in combination, means for detachably piercing and suspending an article to be laundered, and releasing means for said piercing means having an actuator a portion of which overlaps said opening, whereby upon imparting to said device a swinging movement laterally of the supporting rod said actuator is operated by the part of the supporting rod by which the device is feathered on the rod as stated.

45 12. A device of the kind described having a structure defining a non-circular opening shaped to permit the device to be slipped along a supporting rod or the like having other than a circular cross section, whereby the device is suspended from and in effect feathered on said rod, the device including a loop portion and a plate portion for carrying the working parts of the device, the loop portion and plate portion forming between them said shaped opening, the working parts of the device including pinning means, means for maintaining said pinning means operative, and releasing means for the last-mentioned means including a member movable on said plate portion and projecting into said shaped opening so as to be engaged and moved by the rod thereby to actuate the releasing means when and only

when the device as a whole is swung about the rod.

13. A sorting device having a shaped opening whereby the same may be suspended by a suspending means having an offset and yet to permit a pivotal movement of the device about its point of suspension, said device including, in combination, means for detachably piercing and suspending an arti-

cle to be laundered, and releasing means for said piercing means, said releasing means including a movable part adjacent said shaped opening for engagement by such offset on imparting a pivotal movement to the device about its point of suspension thereby to move said movable part to operate said releasing means. 10 15

JOHN EVANS.
